GEORGE B. FRENCH, OF SOUTHAMPTON, NEW YORK, ASSIGNOR TO FRENCH ELECTRIC CO., INCORPORATED, OF NEW YORK, N. Y., A CORPORATION OF NEW YORK

MICROPHONIC TRANSMITTER

Application filed April 12, 1926. Serial No. 101,258.

My invention relates more particularly to an improved method and apparatus for accurately transmitting sound waves or waves adapted for the reproduction of sound waves 5 in an electro-magnetic receiving instrument. In other words, my improvement relates to the employment of means capable of cooperation with a microphonic element in the transmission of sound waves of pure tone and 10 adapted to be reproduced more clearly and accurately than has been possible by the ordinary transmitting and receiving apparatus heretofore in use.

Heretofore it has been common practice, 15 both in the transmitter and receiver, to use a diaphragm having a smooth surface, with relatively high reflecting qualities, and capable of considerable amplitude of mechanical vibration. Such a diaphragm is usually fastened at its periphery and, in the case of the transmitter, is adapted to be vibrated in response to the mechanical air pressures of sound waves impinging on the diaphragm. In the case of the receiver, the diaphragm is 20 adapted to respond to the varying pull of a magnet controlled by an electric circuit of variable strength.

In the ordinary microphonic transmitter, the diaphragm is adapted to vibrate with 25 considerable, though varying, amplitude when sound waves enter the mouthpiece of the transmitter, and these vibrations of the diaphragm are adapted to vary the pressure upon the contacts between carbon particles 30 or granules of the microphonic element, and thereby to vary resistance to a current passing therethrough. Flow of the current, therefore, will correspond more or less to the movements or vibrations of the diaphragm, which correspond in general to the sound waves striking the latter.

These variable currents of the microphonic element upon passing through a coil surrounding the magnet in the receiver, will cause 40 the diaphragm of the receiver to vibrate magnetically, according to the variations in the strength of the current and thereby reproduce vibrations corresponding to the original sound vibrations impressed upon the diaphragm of the transmitter.

It has been customary in prior devices to use diaphragms, in both the transmitter and the receiver, which have a considerable range of vibratory movement and also since the surfaces of the diaphragms used are usually 55 hard and highly polished, the respective diaphragms are capable of considerable reflective action on sound waves received thereby. This reflective character of the usual diaphragm, it has been found, will result in considerable interference with the incoming sound waves striking the diaphragm, due to the reflected sound waves interfering with the impinging direct waves.

Furthermore, the effect known as resonance involving distortions and interferences is in evidence in sounds transmitted by the ordinary diaphragm transmitter. These distortions and interferences in the vibrations of the diaphragm which result in complicating the motions in the variable resistance of the microphonic element are not in accord with the primary or original sound waves it is desired to transmit. As a result, these distortions and interferences prevent a pure tone 60 reproduction of the sound waves impinging upon the moving and reflecting transmitter diaphragm. Consequently, the vibrations produced by the diaphragm upon the carbon microphone are not exact reproductions of the 65 original sound waves. There is still a further distortion due to the natural periodicity of the diaphragm. For instance, in the type of diaphragm now in use there is a marked distortion of sound reproduced, due to the 70 fact that the transmitting and receiving diaphragms, which have their peripheries fixed, have a variable amplitude of vibration from the center to the periphery and these varying amplitudes affect the purity of tone reproduction. These various objections and 75 defects of the ordinary transmitter may be reduced to a minimum or substantially eliminated, and reception materially improved, by using a diaphragm or a solid disc or block 80 with a non-reflecting surface and with a minimum amplitude of vibration, in which the sound waves are preferably transmitted by molecular wave motions within the material 85 of the diaphragm.

Therefore, in overcoming these objections, my invention contemplates the use of a diaphragm, disc or block, forming the transmitting element, of relatively soft or sound-absorbing material, such as wood, cork or the like, and of sufficient thickness to prevent any appreciable amplitude of vibration thereof, as a whole, in response to impinging sound waves. Furthermore, my improvement contemplates minimizing or, to an extent sufficient for practical purposes, eliminating the reflection of sound waves from the surface of the transmitting element, diaphragm or medium. Furthermore, the material used and the relative disposition thereof, as to the microphonic element, is arranged so as to give the diaphragm or transmitting element a minimum amplitude of vibration and, therefore, a natural periodicity of low frequency.

The primary object therefore, of my improvement is to provide a solid transmitting medium adapted to receive and absorb sound waves and thence transmit them, by molecular vibrations within the material, to a microphonic element, the latter being so arranged that variation of the resistance is effected by the pressure of the transmitted molecular waves, whereby the current in a receiving instrument is controlled to reproduce the sounds.

A further object is to provide a solid transmitting medium or element of this character with an absorbing or non-reflecting surface for receiving the sound waves to be transmitted therethrough by molecular waves to the microphonic element.

In carrying out these objects in my improved transmitter, it is found that the objectionable characteristics, hereinbefore referred to, are substantially eliminated and, since the sound waves entering the transmitter are transmitted through a solid medium by molecular vibrations adapted to produce waves exerting pressure upon the variable resistance of the microphonic element, the fundamental tones and over-tones or partials transmitted are clearer and purer and less subject to distortion than those transmitted by the ordinary diaphragm transmitter. As a result of transmitting sounds by my method, it will be understood that the diaphragm of a receiving instrument in connection therewith, will emit sound waves which are clearer and of much greater purity of tone, but of less volume, unless amplified as hereinafter pointed out. For this reason, it will be understood that, on account of the pure tones transmitted, the amount of amplification without distortion may be very much greater, and therefore, my improvement is particularly adaptable for the use of the deaf, for ordinary telephone broadcasting, for radio broadcasting, for making talking-machine records and for other uses

where correct and articulate reproduction of sound waves is the desideratum, simply by the insertion of suitable amplifying means between the transmitter and the receiver.

In the accompanying drawings, I have illustrated several forms and adaptations for carrying out my improvement, together with amplifying circuits, adapted to include a form of my improved transmitter. Fig. 1 shows one form of my improved transmitter, in which the diaphragm is made up of a thick disc of relatively soft material, such as wood or cork; Fig. 2 is a side elevation of a modification, which may be substituted for the ordinary telephone transmitter; Fig. 3 is a horizontal section of the form shown in Fig. 2; Fig. 4 is a wiring diagram, showing the arrangement as applied to the ordinary pocket phone for the deaf, and Fig. 5 is a wiring diagram illustrating amplification of the transmitted sounds by the use of radio tube circuits.

Referring more particularly to the form shown in Fig. 1, it will be seen that my improvement is applied to the ordinary type of microphone transmitter, wherein the casing 1 is preferably provided with a cylindrical elongation 2 to provide for mounting therein a disc 3 of wood, cork or other suitable material, of a character to absorb and then to transmit the sound waves by molecular vibrations of the material. It will be seen that the diaphragm or disc 3 is preferably made of sufficient thickness to practically eliminate vibrations of the diaphragm as a whole. In the present instance, the disc 3 is shown as held in place by the front section 4 of the casing, which is preferably spaced away from surface of the disc to form a compression chamber 5, substantially as shown in Fig. 1. The usual mouth piece 6 is screwed into a bushing 7, surrounding the perforations 8 in the front casing 4, so that air sound waves entering the mouth piece may be impressed upon the front face of the disc or diaphragm 3. The front face 9 of the disc 3 is preferably unpolished or even roughened, so as to reduce the reflecting surface to a minimum. If desired, the disc 3 may be relatively thin and have its front surface coated with a suitable sound absorbing material. Obviously, if the disc 3 is made of cork or soft wood, or roughened material, the natural surface of the material receiving the sound waves will be less likely to reflect them and hence absorption and molecular transmission thereby will be more readily effected.

In the present instance, the disc 3 is preferably provided with a pocket or bore in the rear face thereof, formed by an annular flange 10, in which the microphonic element is inserted. This latter preferably comprises a small cup-like container 11 in the bottom of which there is located one of the carbon discs 12. On top of the carbon disc 12, there is

packed a quantity of carbon particles or granules 13, which are preferably packed solid and a second carbon disc 14 is placed on top of the carbon granules 13. The carbon disc 14 engages the bottom of the pocket formed by the annular flange 10 on the rear face of the disc 3, as will be seen in Fig. 1 of the drawings. A lead wire 15 may be connected with the inner carbon disc 14 and another lead wire 16 connected with the outer carbon disc 12 for completing the circuit to the receiver in the usual manner. The microphonic element 11—14 is arranged to fit closely between the rear face of the disc 3 and the wall of the rear casing 1, so that when sound waves as molecular vibrations of the solid material of the disc are transmitted therethrough to the carbon disc 14, the waves thus transmitted will vary the pressure on the carbon particles 13 and thereby vary the current flowing to the receiver, which is adapted to reproduce the sounds, as previously pointed out.

In the form of my improvement shown in Fig. 2, instead of a disc or diaphragm, of wood, cork or similar material, adapted for the transmission of sound waves by molecular vibrations, I have substituted a block of wood 17, which is provided with a pocket 18 in which the microphonic element is mounted. In this form, the carbon discs 19 and 20 are provided with screw threaded terminals 21 and 22 to which the respective leads 23 and 24 may be secured for completing the circuit to the receiver in the usual manner. Within the pocket 18 and between the carbon discs 19 and 20, there is packed a quantity of carbon particles 25, sufficient to completely and tightly fill the pocket and the space between the carbon discs, so that any vibrations within the solid material of the wood block will be transmitted to the carbon particles to vary the resistance in the mass thereof between the carbon discs, thereby varying the flow of current adapted for reproducing the waves in the receiver. In this form of my improvement, the mouth piece 26 is preferably formed of soft material, capable of absorbing sound waves, such as cork or the like.

As previously pointed out, my improved microphonic transmitter is particularly adapted for use in phones for the deaf and a circuit for the usual pocket set is shown in the diagram of Fig. 4. In this diagram, my improved transmitter, substantially as shown in Fig. 1, is represented at 27, as connected in circuit with a battery, 28, the circuit being completed through the primary 29, of an induction coil, the secondary 30 of the induction coil is connected by leads 31 with ear phones 32, which may be of the usual or any preferred construction. With this form of circuit, the vibrations transmitted by my improved microphonic transmitter are amplified by the induction coil 29—30, and reproduced by the

receiver 32 in clear, pure tones, for as previously pointed out, the sound waves reaching my improved transmitter are transmitted through the disc 3 as molecular vibrations or waves of pure tones which may be amplified enormously without distortion, the latter being an essential requirement for a deaf phone. Furthermore, my improved transmitter eliminates extraneous sounds, which in the ordinary deaf phone, produces a continuous humming or crackling noise.

In Fig. 5, I have shown a wiring diagram, wherein amplification is effected by radio tubes and circuits, corresponding substantially to audio amplification in the ordinary radio receiving set. In this diagram, my improved transmitter is represented at 33, and is placed in the primary circuit 34 of an induction coil, the secondary 35 of which is connected with the grid of a radio tube 36. The plate of the radio tube 36 is connected with the primary 37, of a second induction coil, the secondary 38 of which is connected with the grid of a second radio tube 39, the plate of which is connected to the ear phones 40, substantially as indicated in Fig. 5. With radio tube amplification, as just described, it has been found that the pure tones delivered or transmitted by my improved transmitter may be readily amplified, enormously, without distortion and without interference from over-tones or extraneous sounds, which, as with the ordinary transmitter, might interfere with clear reception.

It will be understood that while I have shown various forms and adaptations of transmitters for carrying out my improved method of transmission of sound waves, through waves of molecular vibrations in a solid medium, I do not wish to be limited to the particular forms shown, for these are merely illustrative and various modifications and adaptations may be employed without departing from the spirit and scope of the invention.

I claim:—

1. A microphonic transmitter comprising a block of solid material upon which sound waves may be impressed, the block of material being adapted to absorb sound waves and transmit them as molecular vibrations within and through the material, a mass of closely packed finely divided microphonic material arranged to receive said molecular vibrations and transform them into variable electric currents for operating a receiver, substantially as described.

2. A microphonic transmitter comprising a block of solid material upon which sound waves may be impressed and transformed into molecular vibrations within the material and closely packed finely divided microphonic material adapted to receive said molecular vibrations and transform them into

variable electric currents for operating a receiver, substantially as described.

3. A microphonic transmitter comprising a solid block of material adapted for transmitting sound waves impressed thereon by molecular vibrations within the material, the sound receiving face of said transmitting block of material being arranged and adapted to absorb sound waves, and a microphonic variable resistance conductor of solidly packed finely divided material mounted in cooperative relation with said solid transmitting block of material, whereby said molecular vibrations set up therein are adapted to vary the resistance in the microphonic material and thereby vary the electric current passing therethrough, for the purpose specified.

4. A transmitter for sound waves comprising a block of solid material adapted to transmit sound waves impressed thereon by transforming them into molecular vibrations within the material and transmitting them therethrough, and means associated with said block whereby said molecular vibrations within the material thereof are adapted to vary the resistance in a mass of solidly packed microphonic material and thereby transmit variable electric currents, for the purpose specified.
